UNITED STATES PATENT OFFICE.

REESE HOWARD, OF SALT LAKE CITY, UTAH TERRITORY.

AUTOMATIC GAS-EXTINGUISHING APPARATUS.

SPECIFICATION forming part of Letters Patent No. 392,921, dated November 13, 1888.

Application filed May 2, 1888. Serial No. 272,590. (No model.)

To all whom it may concern:

Be it known that I, REESE HOWARD, a citizen of the United States, residing in Salt Lake City, Utah Territory, have invented certain 5 Improvements in Automatic Gas-Extinguishing Apparatuses, of which the following is a specification.

My invention relates to that class of devices or apparatuses which are designed to extinguish a gas-light at a certain hour, and the object is to provide a simple and efficient device that may be mounted on an ordinary gas-burner and connected with an ordinary alarm-clock, such as may be purchased in any city 15 for a small sum.

My apparatus is designed to be wound up and connected on the one side, by a cord or other connector, with the gas-cock, and on the other side, by a cord or similar connector, 20 with the vibrating hammer of an alarm-clock. The first movement of the hammer when the alarm sounds releases the spring of the extinguisher and allows it to wind up or actuate the connector attached to the gas-cock, and 25 thus shut off the gas.

In the drawings, which serve to illustrate my invention, Figure 1 is a general view on a small scale, showing the relative arrangements of the gas jet and cock, the extinguisher, and 30 an alarm-clock for setting the extinguisher in motion. Figs. 2 and 3 are respectively a sectional side elevation and a rear elevation of the extinguisher.

In the drawings, X represents an ordinary 35 alarm-clock—as an “Ansónia” clock, for example.

Y represents the extinguisher as a whole, and Z represents the gas-cock.

Referring to Figs. 2 and 3, I will describe 40 the simple spring-motor device, which I call the “extinguisher.” *a a a* represent the parts of a suitable frame, in which is mounted an arbor or shaft, *b*, which is driven by an ordinary clock or watch spring, *c*, in the usual 45 way with the mechanism of spring-clocks. On this arbor is ratcheted a toothed wheel, *d*. By “ratcheted” I mean that when this wheel is held fast the arbor may be rotated, in order to wind up the spring *c*, a pawl, *e*, on the wheel 50 engaging the teeth of a ratchet-wheel, *e'*, carried by the spring-arbor *b*. A spring pawl or dog, *f*, engages the teeth of wheel *d* to form a detent, and this dog is connected by a cord,

g, or the like with the vibrating hammer *h* (see Fig. 1) of the alarm-clock X. On the 55 spring-arbor *b* is secured a sheave or drum, *i*, on which is wound a cord, *j*, or the like, the other end of which is attached to the lever-arm or thumb-piece *k* of the gas cock Z.

The extinguisher Y may be mounted and 60 arranged in any convenient manner with respect to the gas-cock and alarm-clock. In Fig. 1 I have shown it attached to the chandelier or drop-light and near the gas cock.

In winding up the extinguisher the operator 65 unwinds cord *j* from sheave *i*. Then when the gas is turned on the slack in the cord is taken up, or nearly so. When the alarm sounds, the vibrating hammer *h* draws the dog or detent *f* out of engagement with the teeth of wheel 70 *d*, thus releasing it, and this allows the spring *c* to rotate arbor *b* and the sheave *i* thereon, and thus wind up cord *j* and shut off the gas. The cord *j* might wind directly on the arbor *b*; but when it winds on a sheave on the arbor a 75 less number of turns is required to wind up the necessary length of cord. The spring may be wound up by means of an ordinary thumb-piece, *l*, on the end of arbor *b*.

Having thus described my invention, I 80 claim—

1. An automatic gas-extinguishing apparatus comprising an alarm-clock with a vibrating hammer, an extinguisher, as Y, comprising a spring-arbor and spring, a detent connected to the vibrating hammer of the clock, whereby the movement of said hammer releases said detent, and a cord or the like connecting said spring-arbor with the arm of the gas-cock, whereby when said detent is released 90 the spring winds up said cord and shuts off the gas.

2. The combination to form an extinguisher, Y, of a rotatively-mounted spring-arbor, *b*, a spring, *c*, to drive said arbor, a toothed wheel, 95 *d*, ratcheted on said arbor, a detent, *f*, engaging said wheel, its cord or connector *g*, the sheave *i*, and the cord or connector *j*, wound thereon, substantially as set forth.

In witness whereof I have hereunto signed 100 my name in the presence of two subscribing witnesses.

REESE HOWARD.
